UNITED STATES PATENT OFFICE.

EDWARD A. WEBSTER AND LUCIUS O. GIBBS, OF CHICAGO, ILLINOIS.

APPARATUS FOR COMMINUTING AND CORRODING LEAD.

SPECIFICATION forming part of Letters Patent No. 406,378, dated July 2, 1889.

Application filed April 2, 1888. Serial No. 269,350. (No model.)

To all whom it may concern:

Be it known that we, EDWARD A. WEBSTER and LUCIUS O. GIBBS, citizens of the United States, residing at Chicago, in the county of 5 Cook and State of Illinois, have invented certain new and useful Improvements in Apparatus for Comminuting and Corroding Lead; and we do hereby declare the following to be a full, clear, and exact description of the same, 10 reference being had to the accompanying drawings, forming a part of this specification.

This invention relates to that type of attrition or comminuting cylinders employed in the manufacture of white-lead pigment directly from the metallic lead, in what is 15 known in the art as the "Versepuy process," and in which small particles of metallic lead are introduced into a revolving drum or cylinder that slowly turns to cause an attrition 20 of the lead particles upon each other until reduced to a pulp, air or oxygen gas, as well as carbonic-acid gas, being introduced in proper quantities into the interior of the drum to oxidize and carbonate the pulp and 25 convert it into a white carbonate-of-lead pigment; and the object of the present improvement is to provide an improved construction of revolving drum or cylinder for such purpose, embodying the features of easy 30 access to the material being operated upon for examination from time to time without stopping the machinery, perfect ventilation, so as to regulate and reduce the heat natural to the chemical action taking place in the apparatus, as well as the regulation of the air 35 admitted to the apparatus. We attain such objects by the mechanism illustrated in the accompanying drawings, in which—

Figure 1 is a transverse section of a comminuting-cylinder to which our improvements are applied; Fig. 2, a longitudinal section of the same; and Fig. 3, a detail elevation of the endless band-track surrounding the cylinder, showing the means for tightening the same.

Similar letters of reference indicate like parts in the several view.

Referring to the drawings, A represents the drum or cylinder formed of staves hooked together by bands *a* and provided with heads 50 *B*, as shown, the whole being provided with an incorrodible earthenware lining *C*, formed

with longitudinal ridges *c*, that act to lift the particles of lead to effect a more extended attrition of the particles among themselves. The cylinder *A* is shaftless, and is supported 55 by and rotated between pairs of roller *D* *D'*, journaled in the floor-timbers *D²*, as shown, motion being communicated to the cylinder through the forward set *D* of such rollers. Each head *B* is formed with a central orifice 60 *B'*, that is closed by a removable door or man-head *E*, secured in place in the rabbeted recess in the head by means of turn-buttons *e*, or other equivalent means, so that either or both of such man-heads can be readily removed to admit of a ventilation of the cylinder or an inspection of the material while undergoing treatment. The feature of a shaftless cylinder with axial or central openings in the heads thereof is the material part 70 of the present invention, in that as so constructed it effects the following important results in the mode of operation of the apparatus: The material while under treatment can be inspected through the man-hole 75 without stopping the apparatus; that the requisite amount of oxygen for the chemical changes which take place is drawn from the surrounding air, thereby avoiding the use of suction or forcing devices, and the air thus 80 taken prevents the material subjected to treatment from becoming unduly heated, as the drafts through the apparatus carry with them any excess of heat, such inspection consisting in the introduction of a ladle to remove 85 a quantity of the material for close inspection, and chemical examination, if necessary, as well the introduction of the hand or head to closely inspect the whole body of material, while the apparatus is in operation, such access 90 being feasible on account of the size of the apparatus, which will have a usual diameter of five feet, with man-holes twenty inches in diameter, more or less, in accordance with the circumstances, size, and capacity of the 95 plant.

F are a series of register-openings through the man-heads, through which air is admitted to the material being operated upon to furnish the required amount of oxygen to effect 100 the proper oxidation of the same; and in order to regulate and control the amount of air

admitted these openings are provided with adjustable slides or covers F', by which the areas of the openings are regulated.

G is the induction-pipe for the carbonic-acid gas employed in converting the material undergoing treatment into a carbonate. This pipe passes horizontally through one of the heads, and extends into the cylinder A, axially to or near the middle of the same, its 10 end being open. With this construction the gas is evenly distributed to all portions of the material.

The bands *a a*, that form the endless track for the cylinder, are formed with lapped tongues *a' a'*, as shown in Fig. 3, and the ends are connected together adjustably by tightening-bolts *a² a²*, arranged to pass through laterally-arranged lugs or ears *a³ a³* upon the bands. As so arranged, the adjusting mechanism *a²* 20 *a³* will not project into the path of the carrying-rollers D D', but will pass at the sides of the same. A substantially similar provision will be made in connection with the other hoops of the cylinder to take up any slack 25 that may occur in the same.

Having thus fully described our invention, what we claim as new, and desire to secure by Letters Patent, is—

1. An apparatus for corroding and comminuting lead in the Versepuy mode of manufacturing white lead, the same consisting of a shaftless cylinder or drum supported on carrying-rollers and provided with axial openings or man-holes, essentially as set forth.

35 2. An apparatus for corroding and comminuting lead in the Versepuy mode of manufacturing white lead, comprising, in combination, a shaftless cylinder or drum supported

on carrying-rollers, a lining C for the same provided with longitudinal ribs, an axially-arranged gas-introducing tube extending to or near the middle of the cylinder, and axially-arranged removable man-heads E, closing central man-holes in the cylinder-heads and adapted to permit of the inspection, &c., of the 40 material during the rotation of the cylinder, essentially as described, and for the purpose set forth.

3. An apparatus for corroding and comminuting lead in the Versepuy mode of manufacturing white lead, comprising, in combination, a shaftless cylinder or drum supported on carrying-rollers, a lining C for the same provided with longitudinal ribs c, an axially-arranged gas-introducing tube extending to 45 or near the middle of the cylinder, and removable man-heads closing central man-holes in both the heads of the cylinder and provided with a series of adjustable openings, essentially as described, and for the purpose set 50 forth.

4. An apparatus for comminuting and corroding lead, consisting of a shaftless cylinder or drum supported on carrying-rollers and provided with band-tracks *a a*, having lapped 55 tongues *a' a'*, laterally-arranged lugs *a³ a³*, and tightening-bolts *a² a²*, as described, and for the purpose set forth.

In testimony whereof witness our hands this 24th day of March, 1888.

EDWARD A. WEBSTER.
LUCIUS O. GIBBS.

In presence of—

ROBERT BURNS,
GEORGE H. ARTHUR.
